AUTOMATIC WORK STOP FOR PUNCH
PRESS DIESHarry E. Dahlstrom and John L. Olson,
Minneapolis, Minn.

Application November 17, 1949, Serial No. 127,876

4 Claims. (Cl. 164—86)

1

This invention relates to punch presses and dies, and particularly to a stop mechanism associated with the dies of the press and operated by action of the punch for gauging and precisely controlling the intermittent movement of the sheet metal or other strip stock as the latter is manually or automatically fed through the die for each successive punching operation.

It is an object of our invention to provide automatic stop mechanism of the class described, which may be quickly and easily applied to various types of dies, which is readily and accurately responsive to the action of the press and which is adapted to stop the stock in a desired precise relationship after each successive operation of the punching mechanism causing the stock to be precisely held during the next punching operation.

A further object is the provision of a work or stock-stop of the class described which is readily adjustable for blanking dies of various dimensions and size, which may be readily applied to the stripper plate of such dies and which comprises a minimum number of working parts, essentially a spring fulcrum, mounting and tensioning member and an actuating lever mounted therein.

Another object is the provision of an automatic work stop of the class described wherein the stop-carrying lever is longitudinally slidable by hand manipulation for adjustment to accommodate any width of strip or plate used on a set of dies.

Still another object is the provision of a stop mechanism wherein the multifunction spring element urges the stop-carrying arm of a lever into interlocking position and also into centered position towards the receiving end of the stock-guiding channel.

These and other objects and advantages of our invention will more fully appear from the following description made in connection with the accompanying drawings, wherein like reference characters refer to similar parts throughout the several views and in which:

Fig. 1 is a side elevation showing a set of punching dies applied as positioned in a punch press and with the punch in extreme position and having our stop applied thereto;

Fig. 2 is a top plan view of the die set with the punch removed showing an embodiment of our invention applied;

Fig. 3 is a bottom plan view of the essential elements of our automatic stop detached;

Fig. 4 is a side elevation of the same;

Fig. 5 is a fragmentary end elevation of the combination clip and attachment member for my stop lever bar with the bar detached therefrom;

Fig. 6 is a top plan view of a somewhat different

2

and simplified form of combination clip fulcrum and attachment member for the stop bar; and

Fig. 7 is a fragmentary side elevation of the same with the bar therein.

5 As shown in the drawings, our work stop mechanism is applied to a conventional set of dies of a punch press having the usual horizontal bed plate 6 on which is mounted the supporting die 7 and stripper plate 8. Stripper plate 8 is made in 10 conventional manner of two sections having a transverse work-guiding channel 8a formed therebetween through which the stock may be intermittently run or projected. The stripper plate 8 is slidably mounted on a pair of upstanding leader pins 9 and coil springs 10 surround at least 15 two of said leader pins interposed between the base plate and stripper plate to urge the stripper plate upwardly. Suitable elements 11 are fixed to the supporting die 7 and the base plate as desired.

20 Above the lower dies and stripper plate is mounted a conventional type of punch plate 12 having at its rear a pair of large, sliding sleeves 12a which surround the vertical leader pins 13 with working clearance. Punch plate 12 carries 25 in depending relation thereto the usual punch 12b which is vertically aligned with the female dies disposed therebelow. All of said above recited structure is conventional in die sets for punch presses.

30 Our automatic work stop mechanism is extremely simple, comprising as essential parts an elongated lever bar 14 carrying a pivoted upstanding stop pin 15 and a combination mounting plate, fulcrum and spring member 16. Lever bar 14 is preferably in the form of a rigid, straight narrow bar disposed substantially horizontally and edgewise with respect to the base plate 6 and stripper plate 8. The bar is of small oblong cross section and preferably has formed in the upper longitudinal edge thereof, a series of retaining notches 14a for engagement with a small, depending detent 16a formed in the upper portion of the combination clip, fulcrum and mounting member. At the inner end of lever bar 14 the stop dog 15, 35 as shown in the form of an upstanding stud or pin, is pivoted by a rivet or other means 15a; said dog as shown, having a bifurcated attachment portion or clevis 15b which straddles the extremity of lever bar 14 and is pivotally secured thereto with freedom for swinging on a horizontal axis disposed normal to the side surfaces of the bar.

40 The combination clip, fulcrum and attachment member 16 is preferably made from an integral piece of spring metal such as steel and having an upper flat attachment plate 16b provided with

45

apertured ears through which screws 18 may be inserted to threadedly engage tapped sockets in the stripper plate for clamping the combination member 16 against bottom of the stripper plate and adjacent the forward edge thereof. The spring member 16 is curved outwardly and downwardly from the outer edge of the attachment plate 16b to form a lever-accommodating arcuate portion 16c and this medial or lever-accommodating portion is slotted circumferentially as clearly shown in Figs. 2 and 3. The integral spring member is then formed at its end disposed oppositely to the attachment plate 16b into a lever-gripping channel 16d. This channel is preferably of a depth at its extremity slightly less than the height of the lever bar 14 and is of a width to snugly accommodate the cross-sectional shape of bar 14 to center the bar in operation and urge the same to the desired transverse position with reference to the bottom of the stripper plate 8. The detent 16a which is struck up from the stock of attachment plate 16b is in the form of a substantially straight edge adapted to snugly fit any one of the notches 14a at the upper edge of lever bar 14 and acting as a fulcrum for the lever 14 during operation. The fulcrum edge 16a as clearly shown in Fig. 5, is inclined slightly from the horizontal to produce a swinging action of bar 14 distorted from the vertical. The bowed spring member 16 is shaped and bowed in such manner as to be tensioned rather strongly when the lever bar 14 is slipped through the slotted accommodating portion 16c and through the lever-retaining channel 16d, whereby the inner end of the lever is normally urged upwardly as shown in Figs. 1 and 4. The gripping channel 16d is offset slightly as shown in Fig. 5 in its inner contour with relation to the slot between the U-shaped portions 16c to accommodate in the position shown, the lever 14 when held in normal work-stopping position, as shown in Fig. 1. The offsetting of this channel with the biasing or inclination of the edge of fulcrum detent 16a causes the lever bar 14 when the dog is released from the hole in the workpiece to twist at its inner end from left to right, facilitating the movement of the work strip to the next predetermined position. The dog 15 fits with clearance through a vertical hole formed in the lower section of stripper plate 8 and this hole and its relationship with the stripper plate and dies is formed when the dies are made and set up so that the dog will be positioned in work-stopping relation snugly against an end of the punched work towards the receiving end of the stock strip as shown in Fig. 2, thereby retaining the stock strip in precise relation with the dies and stripper plate for the next punch operation.

As shown in the drawings, a set of dies for a simpler blanking operation is provided adapted to cut out a substantially key-shaped plate from a strip of sheet metal. The stop dog 15 is adapted to engage the extremity of the opening formed after blanking operation.

To release the stop dog 15 from engagement with the work as the punching operation takes place, an upstanding striker arm 19 is provided at the outer edge of the bed plate 6 as shown being in the form of a metal arm having an out-turned upper extremity and having its lower end rigidly affixed as by screws to the forward edge of bed plate 6. The upper end of arm 19 is positioned to strike the lever bar 14 outwardly of its fulcrum 16a as the stripper plate 8 is moved

downwardly by the action of the punch and punch plate.

In use, our automatic stock mechanism is readily adjusted for the particular set of dies to be used and attachment plate 16b of the combined spring clip member is secured appropriately to the underside of the stripper plate by tapping or drilling the plate at opposite points for insertion of the attachment screws 18. The length of lever bar 14 extending inwardly of fulcrum 16a may be readily adjusted as desired by merely forcing the tensioned end 16b of the spring clip downwardly and sliding the lever bar to the desired adjusted position with the detent and fulcrum 16a engaging the opposite notch. The bottom of the stripper plate is then drilled to accommodate the stock dog 15 in precise position for engagement of said dog with an opening at the guide-receiving end of the punched out portion of the piece of work. On relatively small die sets the outer end of lever bar 14 may be cut off if desired so that it will not objectionably protrude from the punch press and die.

In operation, the peculiar and simplified construction of the multi-function spring clip 16 not only receives and retains the simplified lever bar 14 but applies spring tension to the inner end of said bar to urge the same upwardly into stock stopping or locking position. In addition, the spring clip because of the confining channel 16d retains lever bar 14 and urges the same to a correct position slightly out of perpendicular to the common center line between the attachment apertures of the flat attachment plate 16b of the clip which usually is parallel to the outer edge of the stripper plate. As the stripper plate is depressed in the installation of Figs. 1 and 2, the outer portion of the lever bar 14 is struck by upstanding plate or arm 19 which effects the actuation of the lever bar to release the dog pin 15 from the aperture guide in the work strip. Immediately thereafter, due to the bias laterally upon the bar 14 effected through the inclined fulcrum edge 16a and the relative positioning of the confining channel 16d (see Fig. 5) the bar is caused to laterally shift at its inner end from left to right so that the dog pin cannot enter the same stop location in the work by the return stroke of the press. This action is exceedingly important to perfect functioning of our structure and allows the work to be moved to the next stop position where the pin 15 under the influence of the spring clip moves upwardly to precise alignment with the next aperture. Thus, the work is held in precise desired position through the initial portion of the next blanking or punching operation. As the punch plate and punch move downwardly depressing in said movement stripper plate 8, the outer portion of lever bar 14 strikes the upstanding striker plate or arm 19 which actuates the lever to downwardly swing the inner dog-carrying end thereof, thereby momentarily releasing the work strip after the punch is made and enabling the work strip either by manual feeding or automatic feeding to be progressed to a position for next receiving the punch.

In Figs. 6 and 7 a somewhat different and simplified form of combination clip and fulcrum is illustrated on an installation where the clip is secured to an upper surface of a movable member such as a stripper plate. The clip in this form indicated as an entirety by the numeral 17 has a flat attachment portion 17b apertured at the ends thereof to form ears for screw attachment to a plate and it has an arcuate slotted bar

confining portion 17c, the slot being of a width greater than the thickness of the bar 14 for permitting restricted shifting of the bar therein. The clip 17 instead of employing a U-shaped confining channel for retention and seating of the bar at the opposite side of the fulcrum or detent 17a is merely slotted for a distance sufficient to accommodate the width of the bar, said slot very closely confining the bar as shown in Figs. 6 and 7. The slotted confining portion of the clip is indicated by the numeral 17d. The slot is offset slightly with reference to the center line of the slotted forward portion 17c in the manner illustrated in Fig. 5 with reference to the form first described. The fulcrum detent 17a is struck up from the body of the clip and is formed substantially identically with the fulcrum detent of the first form.

The operation of this second form of our device is identical with that of the form first described.

From the foregoing description it will be seen that our structure is readily and quickly applicable to all conventional types of punch press dies including in some instances forming dies as well as blanking or piercing dies.

It will further be seen that with an irreducible minimum of parts, we have provided a highly efficient automatic stop adapted to be manufactured at very low cost and producing accurate and efficient results.

It will of course, be understood that various changes may be made in the form, details, arrangement and proportions of the parts without departing from the scope of our invention.

What we claim is:

1. An automatic work strip stop for the dies of a punch press having in combination, a multiple function spring clip member having an attachment element for securing the same to the stripper plate of a die set and having a resilient lever-engaging element for retaining and positioning a lever bar, said clip having a fulcrum element protruding from the body thereof and opposed to said lever-engaging element, a lever arm having a cross sectional shape fitted to the lever-engaging element of said spring clip, said spring clip including integrally formed means constituting a spring member extending outwardly from said attachment element and curved reversely for tensioning said lever-engaging element to swing said lever arm in a vertical direction and work stop means connected with the inner end of said lever arm shaped and constructed to pass through a portion of said stripper plate into engagement with an aperture or shoulder portion of a punched piece of work.

2. An automatic work strip stop for the dies of a punch press having in combination, a multiple function spring clip member having an attachment element for securing the same to the stripper plate of a die set and having a bowed tensionable element constituting a spring member extending outwardly from said attachment element and curved reversely with respect thereto and having a channel element for engaging and positioning a lever bar, said clip having a fulcrum edge protruding from the body thereof

adjacent said attachment element and opposed to said channel element, a lever arm having a cross sectional shape adapted to fit said channel element of said clip and of a thickness for interposition between said fulcrum element and said channel element with application of tension to said bowed element, and stop means connected with one end of said lever arm shaped and constructed to pass through a portion of said stripper plate into engagement with an apertured or shouldered portion of a punch piece of work and normally urged thereagainst by said channel element in response to the spring tension of said bowed tensionable element.

15 3. The structure set forth in claim 2, said spring clip constituting an integral member with said bowed tensionable element provided with a medial slot for accommodating said lever arm and a striker element having means for attachment to one of the principal elements of a die set for alignment with the outer portion of said lever arm to actuate said arm for retracting said stop means during the downward movement of the punch plate of a die set.

4. An automatic work strip stop for the dies of a press having in combination a multiple function spring clip having an attachment element for affixation to a member of a die set and having a lever-engaging element resiliently connected with said attachment element and generally opposed thereto for snugly straddling, retaining and positioning a lever bar, said clip having a fulcrum element protruding from the body thereof generally towards said straddling lever-engaging element and having a lever-arm-engaging edge diagonal somewhat with respect to the general plane of said attachment element, a lever arm having a cross sectional shape fitted to said straddling lever-engaging element, work stop means connected with the inner end of said lever arm, the resilient connection of said lever-engaging element with the body of said clip constituting a spring member extending outwardly from said attachment element and curved reversely for urging the inner end of said lever arm toward said work strip after swinging of said arm away from and said diagonal fulcrum edge serving to urge said lever arm laterally and in the direction opposite that of the incoming work strip upon release from an operative position with said spring clip tensioned in the same direction as that of the incoming work strip.
